UNITED STATES PATENT OFFICE.

JONAS NORTHRUP, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER LOOM.

Application filed July 3, 1919. Serial No. 308,385.

To all whom it may concern:

Be it known that I, JONAS NORTHRUP, a citizen of the United States, residing at Hopedale, in the county of Worcester and 5 State of Massachusetts, have invented certain new and useful Improvements in Feeler Looms; and I do hereby declare the following to be a full, clear, and exact description of the invention, such as will enable others skilled in the art to which it appertains to make and use the same.

This invention relates to an improvement in feeler looms and more particularly to an improvement in bobbin chutes therefor.

15 Feeler looms are a type of weft replenishing looms wherein the weft replenishing mechanism operates to insert a fresh supply of filling in the active shuttle when the old filling is exhausted to a predetermined extent, as determined by the filling feeler mechanism. These looms are usually constructed with the weft replenishing mechanism located on one side of the loom and the filling feeler mechanism located on the 20 other side of the loom. Upon the indication of critical or predetermined exhaustion of the filling by the filling feeler mechanism, the weft replenishing operation takes place upon the next succeeding beat-up of the lay. 25 At this time the usual thread parter mechanism is thrown into operation to sever the filling end extending from the selvage to the bobbin. When the exhausted bobbin is ejected from the shuttle it strikes a bobbin 30 chute and is deflected into a receptacle. The bobbin chute usually consists of an apron mounted upon the lay or upon the frame of the loom and serves only the purpose of deflecting the exhausted bobbin.

35 The present invention has for an object to provide a bobbin chute which is mounted in a novel manner, and which may be readily applied to any loom and particularly those which are already constructed and in 40 operation without changing the construction thereof. The invention has for another object to provide a bobbin chute which, in addition to its functions as a bobbin chute, serves as a thread extracting device, which 45 50 will engage the outgoing filling end as the lay beats backward upon the first pick of the shuttle after replenishment, and hold the filling so that as the shuttle travels onward, its movement causes the filling to be pulled

through the shuttle eye. To the accomplishment of these objects and such other objects as may appear, the invention consists in the structure hereinafter described and claimed.

In the drawing which illustrates the preferred embodiment of the invention Fig. 1 is a sectional elevation of a portion of a feeler loom showing the improved bobbin chute and parts immediately associated therewith. Fig. 2 is a section on line 2—2 Fig. 1 viewed in the direction of the arrows.

The improved bobbin chute indicated generally by 10 consists of an apron 11, preferably of metal, and which is pivoted on the pintle 12, supported by a bracket 13 carried by a receptacle 14 and secured there- 70 to by bolts 15.

The receptacle 14 may be any receptacle employed to receive the exhausted bobbins when the replenishing operation occurs, and is in the present instance shown as a metallic 75 receptacle rectangular in cross section and having a cut away portion as shown in Fig. 1, which is designed to permit the receptacle to fit under the ordinary type of stationary bobbin chute. The bracket 13 is of 80 substantial construction and is preferably cast in such a form as to supply the cut away portion of the receptacle 14, so that in reality a receptacle is formed which has a substantially uniform height of wall on 85 all sides. The bracket 13 is provided with ears 16 adapted to fit over the rim portion 17 of the ordinary bobbin receptacle and is also provided with a lug 18 having slots 19 therein which are adapted to fit over heads 90 20 of arms 21. The arms 21 are fastened to a portion 22 of the frame of the loom by the bracket 23 and bolt 24. The receptacle 14 rests upon the floor as shown in Fig. 1 and its position under the loom is regulated 95 by the length of the arms 21 so that the bobbin chute 10 inclines up under the shuttle box 25. In this position when the lay 26 is at the extreme forward point of its beat, and when replenishment occurs, the exhausted bobbin falls from the shuttle box 25, strikes the apron 11 of the bobbin chute 100 and is deflected into the receptacle 14.

The apron 11 is yieldingly held in the position shown in Fig. 1 by a coil spring 27 105 having one end 28 thereof bearing against the front surface of the apron 11 and the other end 29 against the bracket 13. It

sometimes happens that an exhausted bobbin is caught between the bobbin chute and the lay and should this occur the apron 11 is permitted to swing forwardly about the 5 pintle 12, so that no damage can occur and no parts be broken and after the bobbin has freed itself, the apron 11 is returned to its normal operating position by the spring 27.

10 It will be observed that the bobbin chute 10 can be directly mounted upon any receptacle without the use of the bracket 13 and in the drawing a receptacle of the ordinary construction for receiving exhausted bobbins 15 is shown but obviously a receptacle of any desired shape could be used, the only requisite being that when the bobbin chute and receptacle are placed in an operative position, that the bobbin chute should extend up 20 under the shuttle box so that it will successfully operate to deflect a falling bobbin into the receptacle.

When replenishment is indicated, the usual thread parter operates to sever the 25 filling end extending to the selvage at a point near the shuttle, and in the ordinary construction of feeler loom, the severed end is pulled through the shuttle eye by the ejected bobbin as it falls into the receptacle. 30 Occasionally, and in fact frequently, it happens that this filling end is caught between the shuttle and the binder or the front wall of the shuttle box, and is held thereby, so that, as the ejected bobbin falls it does not 35 pull the filling end through the shuttle eye. When the shuttle starts on its flight on the first pick after replenishment it often draws the filling end toward and sometimes into the shed where, if it is allowed to remain, 40 there results a double pick and consequent blemish in the cloth.

It has been proposed heretofore to eliminate these double picks by providing the loom with various types of thread extracting devices, and all of which as far as I am 45 aware were mounted on either the lay or upon a part of the loom frame. These devices operate with more or less uncertainty

depending on the chance of the filling end coming into engagement therewith. 50

In order to eliminate the uncertainty of operation of the thread extracting device, I have provided the bobbin chute 10 with a series of teeth or engaging devices 30. It will be observed that when the lay starts to 55 beat back, and before the shuttle is started on its first pick of the replenishment, that the filling end extending from the ejected bobbin up through the eye of the shuttle is drawn directly across the mouths of the 60 engaging devices 30, so that when the shuttle starts on its flight the filling end is engaged thereby so that further movement of the shuttle acts to pull the filling end through the delivery eye and prevents the 65 formation of double picks.

I believe that I am the first to provide a bobbin chute which does not move with the lay, with thread extracting means, so that as the lay moves backward the filling is 70 drawn into engagement with the thread extracting means. It is also to be observed that the receptacle and bobbin chute mounted thereon form a unit which may be applied to any loom but which is particularly 75 adapted to be applied to looms which are already constructed, in which case the only adjustment needed is to regulate the length of the arm 21 so that the bobbin chute extends up into an operative position under 80 the shuttle box.

I claim:

A loom having, in combination, a bobbin receptacle provided with a cutaway portion, a bracket fitting into the cutaway portion 85 and serving as a continuation of the receptacle to form with the receptacle a substantially rectangular body, a bobbin chute yieldingly mounted upon the bracket, and arms engaging with the bracket and adapted to be adjustably connected with the frame of the loom to maintain the bobbin chute in a definite operative position with relation to the loom. 90

JONAS NORTHRUP.
